(57) **CLAIM**

The ornamental design for a tire, as shown and described.

DESCRIPTION

FIG. 1 is a front-elevational view of a tire according to the claimed design;

FIG. 2 is a sectional view of FIG. 1;

FIG. 3 is a rear-elevational view thereof;

FIG. 4 is a side-elevational view thereof;

FIG. 5 is a enlarged partial view of FIG. 1; and,

FIG. 6 is a perspective view thereof.

In the drawings, the broken lines in FIGS. 1-6 depict portion of the tire that form no part of the claimed design.
